UNITED STATES PATENT OFFICE.

BURTON S. AIKMAN, OF CHICAGO, ILLINOIS, ASSIGNOR TO NATIONAL BRAKE & ELECTRIC COMPANY, OF MILWAUKEE, WISCONSIN, A CORPORATION OF WISCONSIN.

PNEUMATIC GOVERNOR.

1,153,879.

Specification of Letters Patent.

Patented Sept. 21, 1915.

Application filed July 31, 1911. Serial No. 641,417.

To all whom it may concern:

Be it known that I, BURTON S. AIKMAN, a citizen of the United States, residing at Chicago, in the county of Cook and State 5 of Illinois, have invented certain new and useful Improvements in Pneumatic Governors, of which the following is a full, clear, concise, and exact description, reference being had to the accompanying drawings, forming a part of this specification.

My invention relates to controlling devices, more particularly pneumatic governors, such as are employed in connection with air compressing mechanism to control 15 the starting and stopping of the device for operating the air-compressing mechanism, so that a substantially constant pressure may be maintained. In systems of this kind, compressed air is employed as an operating fluid, and, while there are frequent 20 withdrawals from the supply of the compressed air, it is necessary that there be a substantially and practically constant pressure at all times. In the present day, these 25 arrangements are employed very considerably in electric railway systems, particularly for the purpose of operating the brake equipments. A motor compressor is connected with a supply tank to maintain there- 30 in a constant supply of compressed air at the required pressure, this tank being connected with the brake cylinders through a valve, and the motor being controlled to start and stop in accordance with certain variations 35 in pressure.

The subject matter of my invention is a governing unit, which comprises essentially a switch and means for closing this switch when the pressure in the supply tank has 40 been reduced to a minimum, and opening it when the pressure has again reached a predetermined maximum. This switch is either directly in the circuit of the motor for operating the compressor, or in a local control 45 circuit, automatic means being usually provided for placing the load upon the motor gradually, rather than suddenly. The particular nature of the connection between the controlling unit and the motor does not concern 50 this invention, and I shall make no specific reference thereto. In fact, the entire invention herein is confined to a governor *per se*, and this description will be so confined, except as it is necessary to refer to the 55 other parts so that the controlling unit itself

may be properly understood. It is, of course, apparent that it is only desirable, but in this day absolutely necessary, that the compressor motor be controlled entirely automatically, and the prior art is replete 60 with devices for securing this result mechanically or electrically.

It is one of the important objects of my invention to provide a governor which is of simple construction, and which does not rely 65 upon fine marginal operation.

It is a further object of my invention to provide a governor which will be quick acting, that is, will make and break the electrical contacts quickly.

It is also my object to do away with valves as much as possible; in fact, I employ but one valve, and this valve is of simple construction and of positive operation.

It is my further purpose to provide a de- 75 vice in which the wearing parts are few and are easily accessible for the purposes of inspection and repair.

Other features of construction, arrangement and operation will become apparent to 80 those skilled in the art as this description proceeds.

My invention is embodied in the structure illustrated in the accompanying drawings, in which,—

Figure 1 is a side elevational view thereof; Fig. 2 is a plan view thereof, with the cover removed; Fig. 3 is a sectional view taken on the plane of the line 3—3 of Fig. 2 and looking in the direction indicated by 90 the arrows; Fig. 4 is a sectional view taken on the plane of the line 4—4 of Fig. 2 and looking in the direction indicated by the arrows; and Fig. 5 is a detail view which will be referred to later.

Like reference characters are applied to the same parts throughout the various figures.

The body 6 of the casing is primarily in the form of a shelf, which can be mounted in 100 any suitable manner. This shelf has the upright side parts 7, 7, which are spanned at the top by means of a secondary shelf or bridge 8. The part 6 is provided with a circular opening 9, beneath which a diaphragm 10, of rubber or similar material, is clamped, by means of a casting 11, bolts 12, 12 passing through the casting 11 and the part 6 in order to assemble the parts. The casting 11 forms the diaphragm chamber 13, below the dia- 110

phragm 10, and this chamber is provided with an outlet 14, extending through a pipe coupling part 15, for connection with the compressed-air reservoir, as will be pointed out more fully later.

Mountd upon the diaphragm 10 is the piston member 16, this member having a downwardly extending stem 17 passing through the diaphragm for the reception of a clamping nut 18, and in this way the piston is firmly secured to the diaphragm. The piston member has also an upwardly extending stem 19, which is slightly enlarged at the top and which slides with a piston fit in a corresponding alining opening 20 in the bridge 8. A stout coiled spring 21 is disposed between the top of the piston member 16 and the under side of the bridge 8, a collar 22 intervening, as best shown in Figs. 3 and 4. The spring is adjusted by screws 22^a, 22^b. This spring tends to move the plunger downwardly, and it will be noted that this action is against the working tendency of the pressure in the reservoir. The downward movement of the piston member is positively limited by a cap 23 which has threaded engagement with the top of the stem 19 and which engages the upper side of the bridge 8, as illustrated in the drawings. This cap has a further function which will be described presently. The piston member has an axial bore 24 extending entirely therethrough, this bore thus opening into the diaphragm chamber 13. Toward the top, the bore 24 is enlarged for the reception of a thimble 25, which forms part of a valve structure, and which I shall term a valve. This thimble is driven in the enlarged part of the bore, and is thus firmly held in place. A tubular member 26 is arranged to slide in the enlarged part of the bore in the piston member, and is provided at its lower end with an inwardly extending flange 27 which supports the valve-seat packing 28, held in place by means of a plug 29. The flange 27 slides on the outside of the thimble 25 and is provided with by-passes 30, 30, which are open whenever the valve packing is off the top of the part 25, and closed whenever the valve packing is down upon it. Secured upon each of the upright side pieces 7, 7 is a bracket, 31, and these brackets provide bearings for the shafts 32 and 33. Mounted upon the shaft 32 is a trigger 34, one arm of this trigger extending over the top of the bridge and down into the piston member so as to bear upon the plug 29, as clearly illustrated in Fig. 3. The other arm of this trigger is engaged on its under side by a coiled spring 35 which rests in a pocket in an adjusting screw 36 engaging with the body part 6. This adjusting screw may be locked in any desired position by means of a clamping bolt 37, and the tendency of the spring 35 is to raise that arm of the trigger

with which it is in contact so as to force the other arm down upon the plug 29. Upon the shaft 33, a circuit controlling lever 38 is mounted, this circuit controlling lever being broadly in the form of a bell crank lever, 72 and having one arm thereof in latch relation with the trigger 34, as will be described presently. The other arm extends forwardly, and at its forward end it is provided with a double insulating block 39 secured thereto by means of a screw 40. A spring steel plate 41 is clamped between the two parts of the insulating block, the arrangement being reinforced by a sleeve 42, as shown in Fig. 5, and at its end this spring 80 arrangement carries the electric contact member 43. The contact arm which has just been described extends forwardly through a suitable opening into a flaring box 44 of some fireproof material, this box being carried upon the body 6 by means of screws 45, 45. The stationary contact member 46 is secured to a connector 47 by means of a screw 48, this connector being carried upon the box 44 by means of screws 49, 49. In Fig. 3 the movable contact 43 and the stationary contact 46 are shown to be in engagement, and it is pertinent to point out at this time that such engagement is against the natural tension of a spring 50 which is disposed between the bridge 8 and the under side of the forward arm of the circuit controlling lever 38. This spring is prevented from expanding by reason of the engagement of the downwardly extending arm of the circuit controlling lever with the shoulder 51 on the trigger 34. The engaging parts just described are reinforced by hardened steel plates 52 and 53, respectively, 95 since this engagement is an important catch or trigger engagement upon which the operation of the device depends. So long as the trigger 34 is in the position shown in Fig. 3, it will be impossible for the contacts to separate, and it is not until the spring 50 is allowed to expand that such a result occurs.

The cap 23 which has hereinbefore been referred to is provided upon each side with an upward extension 54, between which a cross rod 55 passing over the circuit controlling lever 38 is mounted. The circuit controlling lever 38 is provided with a hardened steel wearing plate 56 under the cross rod 55, so as to form a good wearing surface, 115 since this lever is adapted to be engaged by the rod to bring the electric contacts together in the operation of the device, as will be described presently.

The box 44 is an arc chute for confining the flame that might occur upon the separation of the contacts, and in order to blow out the arc so far as possible, I provide an electro-magnet spool 57 carried upon side pieces 58, 58 which form magnet poles, and which have extensions 59, 59 which are 123

clamped in place by the screws 45, 45. A fiber or asbestos barrier 60 is secured in front of the arc chute upon the inside of the hood 61 which incloses the entire mechanism, and which is pivoted at 62 so that it may be easily raised to reveal the interior. Upon the front of the hood a keeper 62' is provided, and this keeper carries a ring 63 upon which a spring handle 64 is pivoted. This spring handle has two engaging surfaces 65 and 66 for engaging a lug 67 on the part 6, and the surface 65 is nearer the pivot point than the surface 66. When the ring 63 is swung over the lug 67, the handle is so held that the surface 65 may easily slip by the lug 67, and after the ring is in the position shown in Fig. 1, the handle is turned back so that the surface 66 will engage the under side of the lug. This springs the ring, and the parts are held tightly closed.

A suitable conductor 68 leads from the spring plate 41, and, guided in an opening 69 in a lug 70 on the body of the device, it passes out of the casing. The connector 47 has a lead 71 extending therefrom, and this lead connects with one terminal of the electromagnet spool. The other terminal of the spool is connected with a lead 72, which passes out of the casing through an opening in the bushing 73.

I shall now describe the operation of my improved device:

It will be remembered that the diaphragm chamber 13 is always at reservoir pressure, and this is through a choke opening. When there is no pressure in the reservoir the diaphragm 10 is in its lower position and all the other operating parts are in the position shown in Fig. 3. This is the position which closes together the contacts 43 and 46, and which thus closes the motor circuit. As the motor operates, the air compressor builds up the pressure in the reservoir, and consequently the pressure in the diaphragm chamber 13 is gradually raised. As the pressure builds up, the diaphragm 10 rises against the combined tension of the springs 21 and 35. It will be seen that as the diaphragm rises, the piston also rises and the trigger 34 is turned in a clockwise direction (Fig. 3), so that the area of the engagement between the shoulder 51 and the downwardly extending arm of the lever 38 becomes less and less. When the pressure has risen to a predetermined maximum—that is, when the critical point is reached—the circuit controlling lever is released from the shoulder 51 and the spring 50, now free to expand, throws up that side of the lever to place the downwardly extending arm of the lever over the shelf 51^a on the trigger 34 and to separate the contacts 43 and 46. We now have the reservoir at the required pressure—the pressure which is necessary to properly op-

erate the brakes. As the compressed air is used, the pressure is gradually lowered, and it will be understood presently that my device operates to throw the contacts together again when the predetermined minimum pressure has been reached. This operation is as follows: It will be seen that when the downwardly extending arm of the circuit controlling lever is engaged by the shelf 51^a of the trigger 34, the spring 35 can no longer assist the spring 21, and it will be clear that a lesser pressure will keep the diaphragm in its raised position, that is, a lesser pressure than it required to get it there. However, the parts are so adjusted that when the required minimum pressure has been reached, the diaphragm will begin to descend under the influence of gravity and the spring 21. It will be seen that when the diaphragm is in its upper position, the plug 29 of the valve arrangement engages the forward arm of the trigger, and the by-passes 30, 30 are held closed. Just as soon as the diaphragm begins to descend, however, these by-passes are free to open, since the trigger cannot follow the plug, due to the engagement between the shelf 51^a and the downwardly extending arm of the circuit controlling lever. Thus very quickly does the air in the diaphragm chamber 13 rush up through the bore 24 and out through the by-passes 30, 30 to the interior of the casing, which is freely exposed to the atmosphere—and thus very quickly is the pressure under the diaphragm reduced (due to the choke opening) so that the spring 21 may suddenly expand to a considerable extent, bringing down the pressure, and lowering at the same time the cross rod 55. This rod engages the forwardly extending arm 105 of the circuit controlling lever and quickly brings it down so as to close the contacts 43 and 46 together and to bring the downwardly extending arm of the lever over into such position that the rearward arm of the trigger 34 may rise under the tension of the spring 35 so that the shoulder 51 may engage the downwardly extending arm of the circuit controlling lever, the parts being now back in the position shown in Fig. 3. Then again does the motor begin to run and the pressure to rise, as has been described, and the cycle of operations is repeated.

I claim as new and desire to secure by Letters Patent:

1. In a fluid pressure governor, a fluid pressure chamber, a pressure controlled plunger, a spring for balancing the pressure upon said plunger, a valve on said plunger having a passage communicating with said chamber, a spring pressed trigger lever exerting a pressure upon said valve to retain the same in closed position, a circuit controlling lever having a catch for limiting the movement of said trigger lever to allow 130

releasing of the valve upon inward movement of the plunger due to a decrease of pressure in the fluid pressure chamber.

2. In a fluid pressure governor, a fluid pressure chamber having a restricted inlet, a pressure controlled plunger, a spring for balancing the pressure upon said plunger, a valve on said plunger having a passage communicating with said chamber, a spring 10 pressed trigger lever exerting a pressure upon said valve to retain the same in closed position, a circuit controlling lever having a catch for limiting the movement of said trigger lever to allow release of the valve 15 upon inward movement of the plunger due to a decrease of pressure in the fluid pressure chamber and means on said plunger to move said circuit controlling lever to release said trigger lever when said plunger moves 20 farther inward, due to release of pressure by opening of the valve.

3. In a fluid pressure governor, a circuit controlling lever having an open and a closed position, said lever provided with 25 spring means for biasing the lever toward one of said positions, a trigger for engaging said lever and holding it in one of said positions, said trigger provided with spring means for holding it in engaging position, a 30 movable fluid pressure responsive element for moving said lever, a valve for opening and closing a port controlling the pressure on said element, said trigger having means for governing the position of said valve and 35 a connection between said fluid pressure responsive element and said circuit controlling lever.

4. In a fluid pressure governor, a circuit controlling lever, said lever having spring 40 means tending to move it to the open circuit position, a trigger having a latch for holding said lever in closed circuit position, said trigger having spring means for holding the same in position to hold said lever, a movable 45 fluid pressure controlled element, a fluid pressure chamber communicating with said element, said chamber having a restricted inlet for supplying fluid under pressure thereto, a valve governing an opening in 50 said chamber, said trigger having means for holding said valve in closed position and a connection between said circuit controlling lever and said fluid pressure element.

5. In a fluid pressure governor, a fluid 55 pressure chamber having a restricted inlet, a valve controlling the pressure in said chamber, a movable fluid pressure controlled element, subject to the pressure in said chamber, a spring urging said element against 60 the pressure in said chamber, a circuit controlling lever having a spring tending to move it to the open circuit position, a connection between said lever and said fluid pressure controlled element, said lever being operated by said first spring through

said connection and moved to closed circuit position by release of pressure in said chamber, and a trigger having a latch for holding said lever in closed circuit position, said valve being controlled jointly by said trigger and by said fluid pressure controlled element. 70

6. In a fluid pressure governor, a fluid pressure chamber having a restricted inlet, a fluid pressure element, a spring for movement of said element, a valve on said element, having communication with said chamber, a spring pressed trigger controlled by the movement of said valve, said valve held closed by said trigger, a circuit controlling lever held in closed position by said trigger, a spring to open said circuit controlling lever when said trigger releases the same, said lever controlling the trigger to prevent movement thereof, and means connected to said element to move said lever to closed circuit position when said valve is open. 80

7. In a fluid pressure governor, a fixed and a movable contact, a lever bearing said 90 movable contact, a catch on said lever, a fluid pressure chamber, a fluid pressure controlled element, a restricted inlet opening into said chamber, a valve on said element controlling the pressure in said chamber, a trigger engaging the catch on said lever, said trigger having engagement with said valve, a spring urging said trigger against said valve to retain the same in closed position, said catch of the lever preventing the movement of the 95 trigger after said trigger has released said catch to allow opening of said valve by decrease of pressure in said chamber, and means controlled by opening of said valve to move said lever to closed position. 100

8. In a fluid pressure governor, a fixed and a movable contact, a lever bearing said movable contact, a fluid pressure chamber, a fluid pressure controlled element, a restricted inlet for said chamber, a movable valve 110 controlling the pressure in said chamber mounted on said element, said valve normally closed, a spring controlled trigger, a spring for said trigger, exerting a pressure upon said valve to close the same, and to resist the fluid pressure upon said element, an independent spring resisting the pressure of the fluid upon said element, said circuit controlling lever being provided with a catch 115 engaging said trigger to render said first spring inoperative to exert pressure on said element.

9. In a fluid pressure governor, a circuit controlling lever having a catch, a trigger 120 for engaging said catch to hold said lever in closed position, a fluid pressure controlled element controlling the lever and the trigger, means controlled by said trigger governing the fluid pressure on said fluid pressure element, a plurality of resilient means 130

- for resisting the movement of the fluid pressure element, a spring for said lever forcing the lever to open position when said trigger is operated, one of said resilient means being connected to said trigger, and rendered inoperative to exert a resisting pressure upon said element when the trigger is operated, and a connection between said element and the lever for moving the lever to closed circuit position.
10. In a pneumatic governor a stationary contact, a lever, a movable contact mounted on said lever, spring means urging said lever to open circuit position, a trigger having a latch controlling said lever, a fluid pressure controlled means to trip said trigger, a spring for holding said trigger in position to catch the lever, said spring opposing the movement of said fluid pressure means, a valve seat on said fluid pressure element, and a valve co-operating with said seat, said valve being held upon its seat by said trigger.
11. In a fluid pressure governor, a stationary contact, a lever, a movable contact mounted upon said lever, spring means urging said lever to open circuit position, a trigger having a latch for holding said lever in closed circuit position, a fluid pressure chamber having movable pressure controlled means to trip said trigger, a resetting connection between said lever and said fluid pressure controlled means, spring means operating through said resetting connection upon reduction of pressure in said chamber to reset the circuit controlling lever and valve means controlled by said trigger for reducing the pressure upon said fluid pressure means.
12. In a fluid pressure governor, a fluid pressure chamber, a diaphragm forming a wall of said chamber, a piston member connected to said diaphragm, a spring tending to force said piston inward, a pivoted trigger lever, a valve having a seat on said piston, said valve controlling the pressure in said chamber, a spring pressing said trigger into engagement with said valve to hold same on its seat on said piston to assist in the inward movement of said piston, contact mechanism controlled by said trigger, and means for operating said contact mechanism, and for cutting said second named spring out of action when the piston has been moved a predetermined amount.
13. In a fluid pressure governor a fluid pressure chamber, a movable fluid pressure responsive element subject to the pressure in said chamber, a spring tending to move said element inward against said fluid pressure, a valve having a passage communicating with said chamber, opening of said valve releasing the pressure in said chamber, a trigger, a spring for pressing said trigger against said valve and tending to move said element against said fluid pressure, a stationary contact, a movable contact, a lever bearing said movable contact, means on said lever for cutting said last named spring out of action and a connection between said first named spring and said lever.
14. In a fluid pressure governor, a fluid pressure chamber, having a restricted inlet, a piston member subject to pressure in said chamber, a spring tending to move said piston inward, a valve on said piston, said valve having a passage for releasing the pressure in said chamber, a stationary contact, a lever having a movable contact, a trigger having a latch for engaging said contact lever, a connection between said piston member and said trigger, and a connection between said lever and said spring.
15. In a fluid pressure governor, a circuit controlling lever, a catch for said lever, a trigger, a catch on said trigger for co-operating with the catch on said lever, a spring for said trigger, said spring tending to hold said catches in engagement, a fluid pressure chamber, a fluid pressure controlled element movable by increase of pressure in said chamber to trip said trigger, a spring for said element to resist the pressure in said chamber, a spring for said circuit controlling lever, said latter spring tending to move said lever to open circuit position, a valve communicating with said chamber, said valve being operable to relieve the pressure in said chamber and being normally held closed by said trigger, said valve having a valve seat upon said movable element and a connection between said fluid pressure element and said lever.
16. In a fluid pressure governor, a fluid pressure chamber, a movable fluid pressure controlled element governed by pressure in said chamber, a valve, a port communicating with said chamber, said port being controlled by said valve, a circuit controlling lever, a spring therefor, a trigger lever, a spring therefor, said circuit controlling lever and said trigger lever having interlocking means, a connection from said pressure controlled element to said circuit controlling lever and a connection between said trigger and said pressure controlled element.
17. In a fluid pressure governor, a fluid pressure chamber, a movable pressure controlled element, subject to the pressure in said chamber, a valve for relieving the pressure in said chamber, a spring for moving said element inward, a trigger, a spring for said trigger, said spring resisting the outward movement of said element and holding said valve upon its seat, a circuit controlling lever normally held in closed position by said trigger and an operative connection from said element to said lever.
18. In a fluid pressure governor, a fluid pressure chamber, a piston member subject to

- to the pressure in said chamber, a spring for moving said piston inward, a stem connected to said piston, a valve on said stem, a passage through said stem connecting said 5 valve and said chamber, a trigger lever pivoted at a fixed point adjacent, said stem, and having one arm bearing upon said valve, a spring connected to said lever tending to hold said valve against its seat, and to move 10 said piston member inward, a catch on said trigger, a circuit controlling lever, a catch on said lever for interlocking engagement with the catch on said trigger, a spring tending to move said circuit controlling lever to open position and a loose coupling between said piston stem and said circuit controlling lever to move the lever to closed circuit position.
19. In a fluid pressure governor, a fluid 20 pressure responsive element, a circuit controlling lever, a trigger for holding said lever, said trigger controlled by the fluid pressure element, and a valve governing the fluid pressure on said fluid pressure element, 25 operation of said valve being controlled by said trigger.
20. In a fluid pressure governor, a fluid pressure chamber, a movable fluid pressure responsive element, controlled by pressure

in said chamber, a valve controlling the pressure in said chamber, an operative element having two positions, a trigger for holding said operative element in one position, a spring to move said element into its second position, and a loose coupling from 35 said fluid pressure element to move said operative element to its first position, said valve controlled by said trigger.

21. In a fluid pressure governor, a switch lever provided with a latch, means for biasing said switch to open position, a trigger engaging said latch to hold the switch closed means biasing said trigger to latching position, a pressure chamber having a movable wall, an inlet and an outlet, resilient means 40 acting on said wall in opposition to the pressure therein, a valve for said outlet and means co-acting with said movable wall and trigger for holding the valve closed and operating said trigger to release said latch upon increase of pressure in said chamber.

In witness whereof, I hereunto subscribe my name this 27th day of July, A. D. 1911.

BURTON S. AIKMAN.
